UNITED STATES PATENT OFFICE.

FERDINAND KUESTNER, OF BROOKLYN, NEW YORK.

SMOKING-PIPE.

SPECIFICATION forming part of Letters Patent No. 341,150, dated May 4, 1886.

Application filed April 29, 1884. Serial No. 129,704. (No model.)

To all whom it may concern:

Be it known that I, FERDINAND KUESTNER, of Brooklyn, county of Kings, and State of New York, have invented certain new and useful 5 Improvements in Smoking-Pipes, of which the following is a specification.

This invention has reference to an improved smoking-pipe in which the only substances containing nicotine are collected and prevented from entering the stem of the pipe, and in which the parts composing the pipe are detachable, so as to be easily and thoroughly cleansed; and the invention consists of a pipe-bowl having a bottom opening and a longitudinally-perforated neck or socket communicating with said opening, a pipe-stem fitted tightly into a seat at the upper end of the socket, an extension-tube passing through the socket and provided with a slot facing the bottom opening of the bowl, and a screw-cap attached to the lower end of the extension-tube, whereby the stem is firmly secured to the bowl.

In the accompanying drawings, Figure 1 25 represents a side elevation of my improved smoking-pipe. Fig. 2 is a vertical central section of the same, and Fig. 3 is a detail view.

Similar letters of reference indicate corresponding parts.

30 A in the drawings represents the bowl of a smoking-pipe, which is provided with a cover, *a*, and an opening, *a'*, at the bottom of the bowl, connecting the inner space of the same with the longitudinally-perforated neck or socket 35 B, that is made integral with the body of the bowl and extended below and above the same. The upper end of this socket B has a tapering recess or seat, *b*, for the correspondingly tapering end of the stem C. To the stem C 40 is connected a metallic extension-tube, D, by a screw-thread at its upper end. The extension-tube passes downward through the perforation of the socket B, and is retained in the same by a cap, E, screwed onto the lower 45 threaded end of the tube D, whereby the lower end of the stem is pressed into the corresponding recess, *b*, of the socket B, so as to produce a tight fitting of the stem.

The extension-tube D is provided with a slot, *d*, that is in line with the bottom opening, *a'*, of the bowl, so that the smoke can pass into said tube. By this arrangement the

moisture descending from the mouth-piece is collected in the lower part of the tube D and cannot enter the bowl A, because the lower 55 part of the tube is located below the opening *a'*, and from where it can be removed by unscrewing the cap E. The oily nicotine-bearing sediment is also collected outside of the tube D in the lower part of the socket B. 60

By unscrewing the screw-cap E, removing the tube D, and unscrewing the stem C from the tube D, all the parts of the pipe can be easily and thoroughly cleansed.

As there is an annular air-space between 65 the extension-tube D and the socket B, the former is not heated up by contact with the surrounding parts of the socket and bowl; consequently the smoke is cooled in passing through the extension-tube D to the stem C, 70 whereby smoking is rendered more agreeable.

I am aware that patents have been granted for pipes resembling mine in many particulars; but none of these pipes show the annular space located in the bowl and the inner lining 75 connected with the stem in the manner I have described and claimed.

Having thus described my invention, I claim as new and desire to secure by Letters Patent—

The combination of a pipe-bowl provided 80 with a tubular neck open at both ends, said bowl and neck being connected by a duct, and the upper end of said neck having a conical recess, a draft-tube screw-threaded at both ends and provided with an intermediate slot, 85 said draft-tube being of smaller diameter than the interior of said neck, whereby an annular chamber is formed between them, a pipe-stem having an interior screw-thread at its lower end and a conical exterior surface at said end, 90 whereby it is adapted to fit the conical recess of the neck and connect with the screw-threaded upper end of said draft-tube, and a cap connected to the other end of said draft-tube at the lower end of said neck, substantially as described. 95

In testimony that I claim the foregoing as my invention I have signed my name in presence of two subscribing witnesses.

FERDINAND KUESTNER.
